UNITED STATES PATENT OFFICE

2,598,877

TOOL FOR APPLYING AND REMOVING NIPPLES FROM RADIATORS AND THE LIKE

Charles H. Baker, Paterson, N. J.

Application July 1, 1949, Serial No. 102,692

4 Claims. (Cl. 81—71)

1

The present invention relates to improvements in tools for applying and removing nipples, such as union-nipples of radiators, and more particularly relates to the improvement of tools of the type illustrated and described in United States Letters Patent No. 773,462, October 25, 1904.

In the aforementioned patent there is shown a tool generally comprising a wrench receiving portion and a stem having longitudinal channels on the outer surface. The stem is adapted to be inserted into the union-nipple of a radiator or the like when the valve or other fitting is uncoupled, and the channels are adapted to receive internal lugs formed within the bore of the nipple whereby, upon rotation of the tool, the nipple may be screwed into a threaded opening of the radiator or may be unscrewed therefrom.

While such tools are suitable for applying new nipples or removing nipples which are relatively new, these tools are ineffective and inoperative in cases where the nipples have been in use for a considerable period and the lugs therein have corroded.

Accordingly, an object of the present invention is to provide a tool which is effective to apply, remove and reapply either new nipples formed with or without lugs or nipples in which the lugs have corroded.

Another object is to provide such a tool which is simple, rugged and economical in construction.

A further object is to provide such a tool which is practical and efficient in operation.

Other and further objects of the invention will be manifest from the following description and the accompanying drawing.

In accordance with the invention, the foregoing objects are accomplished by providing a tool comprising an exteriorly threaded portion having an annular face at one side thereof, tooth means on the face, and a wrench receiving portion at the other side of the threaded portion. The tool is also formed with a nipple engaging stem, adjacent the face, formed with channels or the like for receiving the internal lugs of a nipple. The tool may be constructed for accommodating two standard sizes of nipples most commonly used. To accomplish this, the tool has a central wrench receiving portion, an exteriorly threaded portion at each end of the wrench receiving portion, and a nipple engaging stem extending outwardly from each threaded portion. The threaded portions are of different diameters and the stems are of different diameters and of a diameter in relation to the diameter of its respective adjacent threaded portion.

2

In using the tool a threaded portion is screwed into the union or coupling nut of the nipple so that the tooth means firmly engage or bite into the seat of the nipple whereby the tool, upon rotation thereof, is adapted to apply or remove the nipple by causing the same to rotate therewith. In the event the nipple still has its internal lugs the stem portion may be utilized either alone or in conjunction with the tooth means for effecting rotation of the nipple, and in the latter case, the lugs hold the tool non-rotatable relative to the nipple during manipulation of the coupling nut for engaging the tooth means into the seat of the nipple.

10 The tooth means may be provided by mounting a plurality of hardened steel pins in apertures formed in the threaded portion of the tool and these pins have pointed ends facing outwardly. Alternately, the tooth means may comprise a plurality of milled or ground points.

In the drawing:

Fig. 1 is a fragmentary elevational view of a tool in accordance with the invention;

Fig. 2 is an end view of the left-hand end of the tool of Fig. 1;

Fig. 3 is an end view of the right-hand end of the tool of Fig. 1;

Fig. 4 is a fragmentary elevational view of a radiator having a union-nipple adapted to be applied or removed by the tool in accordance with the invention;

Fig. 5 is an enlarged sectional view of the nipple and a portion of the tool shown in dotted lines in operative engagement therewith; and

Fig. 6 is a fragmentary elevational view of one end of another embodiment of the invention.

Referring to the drawing in detail and more particularly to Figs. 1 to 3 thereof, there is shown a tool 10 generally comprising a central portion 12, exteriorly threaded portions 14 and 16 at each end of the central portion having undercut or inwardly bevelled annular outer faces 18 and 20, respectively (Figs. 2 and 3), a plurality of teeth 22 on each of the faces, and union-nipple engaging stems 24 and 26 extending outwardly from the faces 18 and 20, respectively.

The central portion 12 is polygonal in cross-section, for example square as shown in dotted lines in Figs. 2 and 3, but may be of any other shape to facilitate engagement thereof by a conventional wrench, as will become apparent hereinafter.

The threaded portions 14 and 16 are of different diameters, each being dimensional for cooperation with the threads of a union or coupling of

a standard inner diameter and thread and the portion 16 having a larger diameter than the portion 14. Preferably, the portions are of diameters corresponding respectively to the inner diameters of the two sizes of the most commonly used unions or couplings.

The teeth 22, as shown, may be provided by forming a plurality of circumferentially spaced apertures 21 in the faces 18 and 20 of the threaded portions 14 and 16, respectively, which extend outwardly parallel to the longitudinal axis of the tool with their outer ends terminating adjacent the outer surface of the stems 24 and 26, and by mounting and securing in these apertures hardened steel pins 23 having pointed end edges forming the teeth 22 which incline toward the longitudinal axis of the tool and serving as tooth means extending outwardly of the faces 18 and 20 adjacent the stems. These pins seat against the bottoms of the apertures 21. An angularly disposed aperture 25 is provided for each of the pin apertures to facilitate removal of worn pins, which may be knocked out of their respective apertures by inserting a tool in the corresponding aperture 25 and tapping the tool with a hammer.

The stems 24 and 26 are of different diameters and of diameters in relation to the diameter of their adjacent threaded portions 14 and 16, respectively. That is, the diameters of the stems 24 and 26 are such that they may be inserted into nipples associated respectively with couplings or unions adapted to receive the threaded portions 14 and 16, respectively. Each of the stems has a pair of longitudinal diametrically opposite channels 28 on the outer surface for receiving internal lugs formed in union-nipples.

In Fig. 4, a portion of a radiator 30 is shown having a nipple 32 threadedly secured in a wall thereof, and a valve 34 or other fitting is detachably secured to the nipple by a union or coupling 36, associated with the nipple to constitute a fitting generally known as a union-nipple.

As illustrated more particularly in Fig. 5, the nipple 32 comprises an exteriorly threaded end 38, an enlarged seat 40 at the other end, and internal lugs 42 in the bore thereof extending longitudinally from the threaded end towards the seat end. The union or coupling 36 is in the form of an interiorly threaded ring having an inwardly extending annular flange 44 for engaging the rear face of the seat 40, which is formed with a central opening through which the threaded end of the nipple extends.

In order to thread the nipple 32 into the radiator wall, the stem of the tool corresponding in size to the nipple is inserted into the bore thereof with the channels 28 positioned to receive the lugs 42 of the nipple. A wrench is applied to the tool portion 12 for effecting rotation of tool and securing of the nipple to the radiator, whereby the union or coupling 36 is positioned between the wall of the radiator and the enlarged seat 40 of the nipple to facilitate securing of the valve 34 thereto. When it is desired to remove the nipple from the radiator, the valve is uncoupled, the tool is again inserted as just described and the wrench is turned to rotate the tool in a direction to unscrew the nipple.

In the event the lugs 42 have corroded to an extent whereby they are not sufficiently strong or suitably shaped to cooperate with the channels 28 to effect unscrewing of the nipple, the coupling nut 36 is screwed on the threaded portion of the tool which is held non-rotatable relative to the nipple until the teeth 22 firmly en-

gage or bite into the seat of the nipple. This may be effected by holding the tool with one wrench, and applying another wrench to the coupling to turn the same. It will be noted that the lugs 42 engaging in the channels 28 will cooperate to hold the tool non-rotatable relative to the nipple during such manipulation of the coupling nut. With the coupling so applied and the teeth firmly engaged with, or embedded into, the nipple seat, a wrench may be applied to the portion 12 of the tool to turn the same and cause the nipple to be unscrewed.

If desired, nipples with corroded lugs can be reapplied to the radiator by following the foregoing procedure. Likewise, the tool in accordance with the invention may be utilized for applying and removing nipples formed without internal lugs.

In Fig. 6, a modified tool 10a is shown which differs essentially from the tool 10 described in connection with Figs. 1 to 3, in that, the annular undercut or inwardly bevelled faces 18 and 20 are formed with milled or ground points or teeth 22a instead of being provided with pins.

The exteriorly threaded portions 14 and 16 in each form may be secured to the stems 26 by any suitable means, such for example, as the pins 46 shown in Fig. 6.

It is to be understood that the annular faces 18 and 20, in each embodiment, may be bevelled to correspond with the bevelled face on the nipple, as shown in the drawing, or may be flat if desired.

From the foregoing description, it will be seen that the present invention provides an improved tool for removing or applying union-nipples and the like which is simple and economical in construction and practical and effective in operation. The tool is adapted to cooperate with nipples formed with or without internal lugs or nipples having corroded lugs which do not afford a grip. The tool is rugged in construction and can readily withstand such rough usage to which it may normally be subjected.

While the tool has been described as having nipple removing and applying means at each end it will be appreciated that the tool could comprise a wrench receiving portion at one end and a single nipple removing and applying means at the other end.

While I have illustrated and described preferred embodiments of my invention, it is to be understood that I do not wish to be limited to those precise forms, as obviously various changes and modifications may be made therein without departing from the spirit and scope of the invention.

What I claim is:

1. A tool of the class described comprising a body member having an exteriorly threaded portion provided with an annular face at one side thereof, said threaded portion having a plurality of bores formed in the said face thereof and extending substantially parallel to the longitudinal axis of the tool and each opening at one end at said face, a pin secured in each of said bores and formed with a pointed end extending slightly beyond said face, said body member having apertures formed in the surface thereof and communicating with the other ends of said bores whereby to receive an implement for effecting removal of the pins for replacement, a union-nipple engaging stem extending co-axially from said portion adjacent said face, and a cross-sectionally polygonal wrench receiving portion

formed on said body member at the other side of said threaded portion.

2. A tool of the class described comprising a body member having an exteriorly threaded portion provided with an inwardly bevelled annular face at one side thereof, said threaded portion having a series of bores formed in said face thereof and extending substantially parallel to the longitudinal axis of the tool and opening at one end at said annular face, a pin secured in each bore and formed with a pointed end projecting slightly beyond said face to provide tooth means, said body member having inclined apertures formed in the surface thereof adjacent said threaded portion and in communication with the other ends of said bores whereby to receive an implement for effecting removal of the pins for replacement, a union-nipple engaging stem extending co-axially from said portion adjacent said face and having longitudinal channels on the outer surface thereof for receiving lugs in the nipple, and an integral cross-sectionally polygonal wrench receiving portion formed on the body member at the other side of said threaded portion.

3. A tool of the class described comprising an exteriorly threaded portion having an annular face at one side thereof, a plurality of teeth on said face, a union-nipple engaging stem extending coaxially from said portion adjacent said face and having longitudinal channels on the outer surface for receiving lugs formed in the nipple, and a cross-sectionally polygonal wrench receiv-

ing portion at the other side of said threaded portion.

4. A tool of the class described comprising an exteriorly threaded portion having an annular inwardly bevelled face at one side thereof, a plurality of teeth projecting slightly from said face, a union-nipple engaging stem extending coaxially from said portion adjacent said face and having longitudinal channels on the outer surface thereof for receiving lugs formed in the nipple, and an integral cross-sectionally polygonal wrench receiving portion at the other side of said threaded portion.
